FEED DEVICE

Harry E. Cullen and Henry O. Ronning, Minneapolis, Minn., assignors to Waldorf Paper Products Company, St. Paul, Minn., a corporation of Minnesota

Application February 12, 1940, Serial No. 318,451

9 Claims. (Cl. 271—1)

Our invention relates to feed devices and particularly to feed devices adapted to feed blanks from a stack to a carton forming or filling device.

An object of the invention resides in providing a feed device which will be extremely positive in action.

A still further object of the invention resides in providing a feed device which will positively eject the blanks one at a time from the stack.

Another object of the invention resides in providing a device in which the blanks are arranged in substantially horizontal position and in which the lowermost blank is ejected from the stack.

An object of the invention resides in providing a separator adapted to be inserted between the lowermost blank and the adjacent blank of the stack and to support the remainder of the stack during ejection of the lowermost blank.

Another object of the invention resides in providing a feed device in which the superimposed blanks are permitted to be lowered only after the lowermost blank has been ejected from the stack.

A feature of the invention resides in arranging the ejector to follow along with the separator and to eject from the stack only the blank disposed beneath the separator.

A still further object of the invention resides in providing supporting means on the ejector for maintaining the edge of the blank to be ejected in a position to be engaged by the ejecting means.

Other objects of the invention reside in the novel combination and arrangement of parts and in the details of construction hereinafter illustrated and/or described.

33 In the drawings:

Fig. 1 is a longitudinal elevational sectional view of a carton forming machine illustrating an embodiment of my invention.

Fig. 2 is a cross sectional view taken on line 40 2—2 of Fig. 1.

Fig. 3 is a plan view of a portion of the structure shown in Fig. 1.

Fig. 4 is a fragmentary elevational sectional view taken on line 4—4 of Fig. 3.

Fig. 5 is an elevational sectional view, similar to Fig. 1, of a portion of the structure shown in Fig. 1 drawn to a greater scale and showing the parts in altered position.

Fig. 6 is a view similar to Fig. 5 showing the parts in still different positions.

Fig. 7 is a perspective view of the blank.

In the feeding of thin blanks from a stack considerable difficulty has been encountered with the feed device feeding two blanks or not feeding any

at all. The present invention overcomes this difficulty by separating the blank to be ejected from the remainder of the blanks in the stack prior to ejection thereof from the stack.

The particular blank, adapted to be formed into a carton by the instant invention designated at 5 31 is shown in detail in Fig. 7, and is constructed from paper board formed with two longitudinal scores 32 and 33 and with two transverse scores 34 and 35 which divide the blank into a bottom 10 36, side walls 37 and 38, and end walls 39 and 40. In addition, the blank 31 is constructed to provide flaps 41 and 42 issuing outwardly from the side walls 37 and 38 and hingedly connected to the same through the scores 34 and 35. These 15 flaps are adapted to be folded over and attached to the end walls 39 and 40 by means of any suitable adhesive such as now used for the purpose. The side walls 37 and 38 may be constructed doubled-over, in which case the edges 43 thereof 20 become rounded. In the erection of the carton the walls 37, 38, 39 and 40 are bent about the scores 32, 33, 34 and 35 until the walls extend at right angles to the bottom 36 and the flaps 41 and 42 25 glued to the end walls 39 and 40. This is accomplished over a suitable form in which the substance to be packaged is contained and thereafter the formed carton, together with the contents of the form removed from the form.

For the purpose of illustrating our invention we 30 have shown in the drawings a portion of a carton forming machine A which is provided with a framework B. Mounted on the framework B is a

rack C for supporting blanks to be formed into cartons. Rearwardly of the rack C is a feed device D which constitutes the inventive feature of the machine and which is operated by a drive mechanism E. The blanks, on leaving the rack C, are formed into cartons in a forming device F.

These various parts will now be described in 40 detail.

The framework B consists of two end frames 10 and 11, identical in construction, which are shown in Fig. 1. The end frame 10 is illustrated 45 in detail in Fig. 2 and consists of two uprights 12 and 13 constructed of angle stock. These uprights are connected together at their upper ends by means of a cross bar 14, all of the parts of which are welded together. In addition, another cross bar 15 extends across the said uprights intermediate the upper and lower ends thereof which may be secured thereto in any suitable manner.

The two uprights 12 and 13 of frame 10 are connected to the corresponding uprights of the frame 50 55

11 by means of two longitudinally extending angle frame members 16 and 17. In addition, to these longitudinal frame members two additional longitudinal frame members 18 and 19 are employed 5 which are constructed from rectangular bars and which extend across the cross frame members 14 and are rigidly bolted thereto in spaced relation.

The rack C is best shown in Figs. 1 and 3 and 10 comprises six uprights 21, 22, 23 and 24. These uprights are constructed of rectangular bar stock and have the upper ends 25 thereof bent outwardly to facilitate insertion of the blanks 31 into 15 the rack. The uprights 21 and 22 are attached to the longitudinal frame members 18 and 19 by means of spacer blocks 44 whereby the said uprights become spaced from the said frame members. The uprights 24 are directly secured to a cross bar 45 which extends across the longitudinal frame members 18 and 19 and which is secured 20 thereto. The uprights 23 are similarly secured to a casting 196 forming a part of the forming device F which will be subsequently more fully described. In Figs. 5 and 6 a number of blanks have 25 been shown, the lowermost of which is designated by the reference numeral 31 and the superimposed ones being designated by the reference numerals 31a and 31b. The uprights 21, 22, 23 and 24 are spaced so as to engage the edges of the said blanks and hold the same in a stack 47 within the rack 30 C. The lowermost blank 31 is supported in a manner to be presently described in detail.

The feed device D consists of an ejector 48 and a separator 49 which are supported and guided for movement in the following manner:

35 The ejector 48 consists of a plate rectangular in form which is best shown in Fig. 5. This plate rests upon two guide bars 51 and 52 which extend across and rest upon the upper surface of the cross frame member 14 of the end frame 40 10. The two guide bars 51 and 52 extend beneath the rack C and are attached to lugs 53 formed on a guide box 54 constituting part of the forming device F. This guide box extends across 45 the two longitudinal frame members 18 and 19 and is secured to the underside thereof. The ejector 48 has secured to it two guide strips 55 of a thickness slightly greater than or equal to the thickness of the guide bars 51 and 52 which 50 slide along the said guide bars and guide the ejector 48 for reciprocating movement along said guide bars. A plate 56, attached to the undersides of the guide strips 55 by means of screws 57 hold the ejector 48 in place upon the guide bars 51 and 52 and prevent movement of the 55 same out of the plane of said guide bars. The guide bars 51 and 52 are of such a height as to support the lowermost blank 31 of the stack 47 in the rack C. Ejector 48, resting upon these 60 guide bars, is in a position to engage the edge 43 of the lowermost blank 31 and to move the said blank longitudinally out of the stack 47. To facilitate such movement the uprights 23 of rack C are spaced from the guide bars 51 and 52 to provide a space 53 through which the blank 31 65 may be ejected. Likewise the uprights 24 of the rack C are spaced from the guide bars 51 and 52 to permit of entry of the ejector 48 into the stack 47. The uprights 21 and 22 may project 70 below the guide bars 51 and 52, if desired.

75 The separator 49 consists of a plate which is shaped as shown in Fig. 3 having a curved leading edge 59 which is formed with a sharpened bevel. This separator overlies the ejector 48 and is closely positioned relative thereto so that the under surface thereof and the upper surface of

the ejector 48 are substantially co-planar. The separator 49 is guided for movement by means of two longitudinally extending guide bars 61 and 62, similar to the guide bars 51 and 52. These guide bars overlie the guide bars 51 and 52 and at their outer ends are supported relative to the same by means of spacer blocks 63. A clamp bar 64 extends across the two guide bars 61 and 62 and bolts 65 extending jointly through said clamp bar, the guide bars 61 and 62, blocks 10 63 and the guide bars 51 and 52, and threaded into the cross frame member 14 of end frame 10 hold the parts rigidly attached to the frame B. Other screws 66 extend through the longitudinal frame members 18 and 19 and are threaded into 15 the clamp bar 64 and stiffen and reinforce the portion of the framework B formed by the frame members 18 and 19. The forward ends of the guide bars 61 and 62 are attached to the underside of the cross bar 45 which supports the uprights 24 of the rack C. In this manner the two sets of guides consisting of the guide bars 61 and 62 and the guide bars 51 and 52 are separated from one another throughout their extent 20 to permit movement of the ejector 48 and the separator 49.

The separator 49 is mounted in a manner similar to the ejector 48 and has attached to it two guide strips 67, similar to the guide strips 55. A plate 68 overlies these guide strips and the 30 guide bars 61 and 62 and is attached to the said guide strips by means of screws 69. In this manner the separator 49 is guided for movement along the guide bars 61 and 62. The ejector 48 is of a thickness substantially equal to the thickness 35 of the blank 31, while the separator 49 may be of any desired thickness. In actual construction we prefer to make the said separator as thin as possible so as to avoid shifting the individual blanks in the stack 47 an appreciable amount. 40 Inasmuch as the beveled edge 59 of the separator 49 is on the upper surface of the same, the lower surface of the said separator at which the sharpened edge is disposed lies in the plane between the lowermost blank 31 and the superimposed blank 31a. It will thus be readily comprehended that, when the separator 49 is advanced along the guides 61 and 62, the same engages in between the edges 43 of the lowermost 45 and the next to the lowermost blank in the stack 50 47 and may enter between the said blanks. The position of the separator, when disposed between the said blanks, is as noted in Fig. 5. When, thereafter, the ejector 48 is moved, as disclosed in Fig. 6, the said ejector is free to engage the 55 lowermost blank 31 and eject the same through the space 58 and into the forming device F.

The drive mechanism E for operating the said feed device D is best shown in Figs. 1, 2 and 3. This mechanism includes a shaft 71, journaled 60 in bearings 72 secured to the longitudinal frame members 16 and 17. Collars 73 on this shaft restrain axial movement thereof. The shaft 71 has mounted on it two cams 74 and 75, which function in a manner to be presently described 65 and which cause movement of the ejector 48 and separator 49.

Extending across the lowermost portion of the uprights 12 and 13 of the frame 10, is a stationary shaft 76. This shaft is mounted in supports 77 70 in the nature of bearings, which supports are secure to the uprights 12 and 13. The shaft 76 is held from movement with reference to the supports 77 by means of set screws 78 extending through said supports and engaging the shaft. 75

Pivots on the shaft 76 is a lever 79 which is constructed with a boss 81 journalled on the shaft. This lever is restrained from axial movement by means of two collars 82 and 83 secured to the said shaft. The lever 79 has rotatably mounted on it a roller 85, which is adapted to engage the cam 75. The lever 79 extends upwardly beyond cross frame member 14 of frame 10 and in between the longitudinal frame members 18 and 19. Pivoted to the upper end of the lever 79 at 86 is a link 87, which is pivoted at its other end by means of pintle 80 to two ears 90, issuing upwardly from and attached to the plate 68. By means of this construction the plate 68 is reciprocated and at the same time the separator 49 which is connected to it, is moved from one extreme position to the other.

A tension coil spring 98 is connected at one end to the lever 79 and at its other end to an adjusting bolt 99 secured to a mounting 101 attached to the frame 11. This spring urges the roller 85 into engagement with the cam 75 and causes the lever 79 to follow the cam as the cam operates.

Mounted on the fixed shaft 76 is another lever 88, similar to the lever 79, which is provided with a boss 89 journalled on the said shaft. Collars 91 hold this lever from axial movement on the shaft. The lever 88 extends upwardly and terminates at a position below the cross-frame member 14 of frame 10. This lever has rotatably mounted on it a roller 92, which engages the cam 74. The upper end of this lever 88 has pivoted to it at 93 a link 94 which extends below the guide bars 51 and 52. This link is pivoted at its other end by means of a pintle 95 to lugs 96 issuing outwardly from the under side of the plate 56. By means of this construction, the plate 56 is reciprocated along the guide bars 51 and 52 and the ejector 48 caused to move from one extreme position to the other.

A spring 102, similar to the spring 98, is connected to the lever 88 and is attached at its other end to the mounting 101. This spring serves the same purpose as the spring 98 and maintains the roller 92 in contact with the cam 74 so that the lever 88 is reciprocated in opposite directions as the cam operates.

50 The two levers 79 and 88 are separated from one another at the location of the two cams 74 and 75 and are bent at 100 and 97 to bring the upper ends of the same into close proximity to procure application of force to the plates 68 and 56 near the centers of the same.

For the purpose of supporting the lowermost blank 31 and preventing the same from bowing downwardly and interfering with the ejection thereof, a support in the nature of a pad 143 is employed which is attached to a bracket 144 extending outwardly from and secured to the plate 56. This pad is preferably of a resilient material such as rubber or the like and the upper surface thereof is level with the upper surface 65 of the guide bars 51 and 52. The lowermost blank is thus maintained with the edge 43 thereof in the proper position to be engaged by the ejector 48. This causes the device to operate in a positive and effective manner.

70 To prevent the blanks from being ejected from the stack 47, when the separator 49 is being inserted between the lowermost blank and the adjacent blank, two stops 127 are employed which are attached to two arms 125 situated adjacent the longitudinal frame members 18 and 19. In-

asmuch as the method of mounting the arms 126 and the construction for operating the same is identical for both of the arms, only that in connection with the arm associated with the longitudinal frame member 18 will be described in 5 detail. The arm 126 is pivoted on a stud 134 secured to the longitudinal frame member 18 and is adapted to swing in an up-and-down direction. The lowermost extremity 135 of the upright 21 of rack C extends below the block 44 10 to which it is attached to form a guide for holding the said arm 126 in proper position. The arm 126 is urged upwardly by a construction, best shown in Fig. 4. Threaded into the cross bar 45 is a bolt 136 which passes freely through 15 the arm 126 and which is formed with a head 137 which becomes situated upon the underside of said arm. A compression coil spring 138 encircles the lowermost portion of this bolt and is seated against the head 137 and against the 20 underside of the arm 126. This urges the arm 126 upwardly.

The arm 126 has issuing from it a stud 139 which has rotatably mounted at the end of it a roller 125. The said stud is bent downwardly 25 so that the roller 25 is positioned beneath the plate 56 attached to the ejector 48. This roller is adapted to engage a cam 124 attached to the plate 56. The cam 124 has a beveled cam surface 141 and a cam surface 142 parallel with the 30 plate 56. As soon as the surface 141 engages the cam roller 125 arm 126 is swung downwardly and the stop 127 moved to a position below the lowermost blank 31 to permit of ejecting the same from the stack 47. During ejection of the 35 blank, the roller 125 engages the surface 142 and maintains the stop in disengaging position. When the plate 56 reaches its extreme retracted position the roller 125 engages the plate 156 and brings the stop 127 into active position where 40 it remains until the cycle is repeated.

Inasmuch as the forming device F does not constitute a particular feature of the invention the same has not been illustrated in detail in the drawings and no mechanism has been shown 45 for operating the same. It will, however, be comprehended that the invention proper may be used to feed carton blank to any sort of a machine which operates upon the blanks and is not to be limited to the specific machine in which 50 the goods to be packaged are inserted into the carton.

The forming device F consists of two castings 103 and 104 which extend transversely of the machine and which are formed with base members 105 and 106 and with end walls 107 and 108. The casting 103 is attached to a table 109 which rests upon the two longitudinal frame members 18 and 19. The casting 104 is attached to a table 111 adjoining the table 109, which table is similarly secured to the longitudinal frame members 18 and 19. The base 106 of casting 104 is spaced from the two guide bars 51 and 52 to provide the space 53, previously referred to, and through which the carton blanks 65 are inserted. In the table 109 is formed an opening 133.

Below the two longitudinal frame members 18 and 19 are provided the guide box 54, previously referred to. This guide box is provided with two 70 vertically extending walls 112 and 113 and a bottom 114 connected thereto. The walls 112 and 113 have lugs 53 secured thereto by means of which the said guide box may be attached to the undersides of the longitudinal frame mem- 75

bers 18 and 19. The two guide bars 51 and 52 are supported on certain of these lugs and terminate at the inner surface of the wall 113 of the said guide box. Other guide bars 115, which 5 form a continuation of the guide bars 51, commence at the inner surfaces of the wall 112 and extend to the other end of the machine. These 10 guide bars are similarly supported. The base 105 of the casting 193 is attached to the guide bars 115.

In the guide box 54 is mounted a plunger 116 which has attached to it a vertically extending tube 117. Tube 117 is guided for vertical reciprocating movement relative to the guide box 54 15 in a guide 118 attached to the underside of the bottom 114 of the said guide box. Within this tube is slidably mounted a rod 119 which has attached to the upper portion thereof an engaging member 121. Both the plunger 116 and the 20 engaging member 121 are independently movable and may move up to the surface of the tables 109 and 111.

The packaged goods are removed from the forming device F by means of the following construction: Attached to the upper surface of 25 the table 109 are two angle-shaped guides 146 and 147 which extend up to the edges of the opening 133. On the table 111 is disposed a pusher 148 which has a base 149 slidably mounted in guides 151 attached to said table. This pusher has two boxes 152 extending upwardly therefrom through which a shaft 153 extends. Shaft 153 has pivoted to it at its ends two links 154 which extend in a direction away from the 30 rack C.

In operation the rack C is filled with blanks, as indicated in Figs. 5 and 6, and the machine set in operation. Normally both the separator 49 and the ejector 48 are in the positions shown 35 in Fig. 1 and toward the right end of the machine. As the shaft 71 rotates, cam 75 moves in a clockwise direction, as shown in Fig. 1, and spring 98 urges lever 79 to move toward the left. This moves the separator 49 in between the lowermost blank 31 and the adjacent blank 31a until the said separator reaches the position 40 shown in Fig. 5. During such movement the stops 127 are in their upper positions and restrain movement of the blanks out of the rack 45 C. During such movement of the lever 79 the roller 92 rides on the circular portion of the cam 74 and remains stationary. When the parts 50 are in the position shown in Fig. 5 the cams at the locality designated by the reference numeral 55 122 are engaging the rollers 85 and 92. As the shaft 71 continues to rotate, lever 88 is moved toward the rack C and lever 79 remains stationary. During such movement the ejector 48 55 engages the edge 43 of the lowermost blank 31 and shifts said blank out of the rack C and through the space 58 and into the compartment 123 formed between the two castings 103 and 104. As soon as the lever 88 commences to move 60 the wedge-shaped cams 124 thereon engage rollers 125 and swings the arms 126 downwardly. This lowers the stops 127 and frees the lowermost blank 30 which may thereafter be ejected through the space 58 and into the compartment 123 as described. The position of the blank 31, 65 when partly ejected from the stack 47 is shown in Fig. 6. Movement of the lever 88 continues until the blank has been moved to a position where the same is centrally over the plunger 116. A metal form containing the commodity to be 70 packaged, which is indicated at 128 in Fig. 1, is 75

inserted into the box guide 54 above the plunger 116. This form has channel-shaped members 129 at the edges thereof which engage lugs 131 on the plunger 116. The form 128 is so proportioned that the same comes immediately beneath the bottom 36 of the blank 31. As the plunger 116 is raised the sides 37 and 38 of the blank are folded inwardly and likewise the ends 39 and 40 by means of walls 132 similar to the walls 107 and 108. The walls of the carton are thus caused to fold about the form 128 and as upward movement of the plunger continues the folded carton becomes ejected through the opening 133 in the table 109.

After the carton has been formed about the 15 form 128 and the same ejected through the opening 133 and to the upper surface of the table 109 the engaging member 121 and the rod 119 are maintained in elevated position while the plunger 116 is lowered. During such move- 20 ment the lugs 131 engage the channel-shaped member 129 of the form 128 and withdraw the same from within the carton, leaving the goods packaged in the carton. The packaged goods are then removed from in a position over the 25 opening 133 and table 109 and shifted along said table. When the links 154 are moved toward the left, as viewed in Fig. 6, the completed pack- 30 age resting upon the engaging member 121 is shifted along on top of the table 109 between the guides 146 and removed from a position over the hole 133 to permit of a repetition of the cycle of operations.

The advantages of our invention are manifest. The device is exceedingly simple in operation 35 and can be constructed at a nominal cost. By means of the separator used positive feeding of the blanks from the stack is procured. With our invention there is no danger of the device feed- 40 ing two blanks or failing to feed a single blank. While the lowermost blank is being ejected from the rack the remaining blanks are positively sup- 45 ported throughout the larger area thereof by the separator. By the use of the stops it becomes impossible to eject the blanks while the sepa- 50 rator is inserted between the lowermost blank and adjacent blank.

Changes in the specific form of our invention, as herein disclosed, may be made within the 55 scope of what is claimed without departing from the spirit of our invention.

Having described our invention, what we claim as new and desire to protect by Letters Patent is:

1. In combination, a rack for supporting a stack of planiform blanks each arranged in a substantially horizontal position, upper and lower spaced guides parallel with the planes of the blanks, a plate-like separator guided for movement along the upper guide, said separator being adapted to enter between the lowermost blank and adjacent blank to support the portion of the stack above the lowermost blank, a plate-like ejector slidably mounted on said lowermost guide and having a portion adapted to engage an edge of the lowermost blank for ejecting the same from the stack, the lowermost surface of said separator and the uppermost surface of said ejector being substantially coplanar.

2. In combination, a framework comprising a pair of longitudinally extending frame members, an end across frame member at one end of the longitudinal frame members, two spaced intermediate cross frame members situated intermediate the ends of the longitudinal frame members, a lower guide secured to the end cross 70 75

frame member and extending parallel with said longitudinal frame member, means for supporting said guide at its other end, a second guide superimposing said first guide and supported at 5 one end by said end cross frame member, said second guide being attached to one of said intermediate cross frame members at its other end and being spaced from the first named guide throughout the greater portion of its extent and 10 at the locality of attachment thereof to the intermediate cross frame member, uprights secured to said longitudinal frame members and to said intermediate cross frame members to form a rack for the reception of a stack of blanks, said first 15 guide forming a bottom for the rack, a plate-like separator disposed upon the underside of said second named guide and adapted to be moved in between the lowermost blank and the adjacent blank, an ejector disposed upon the uppermost 20 guide and adapted to engage an edge of the lowermost blank, and means for guiding said separator and ejector for movement along said guides.

3. In combination, a framework comprising a pair of longitudinally extending frame members, 25 an end cross frame member at one end of the longitudinal frame members, two spaced intermediate cross frame members situated intermediate the ends of the longitudinal frame members, a lower guide secured to the end cross frame 30 member and extending parallel with said longitudinal frame members, means for supporting said guide at its other end, a second guide superimposing said first frame member and supported at one end by said end cross frame member, said second guide being attached to one of said intermediate cross frame members at its other end and being spaced from the first named guide throughout the greater portion of its extent and 35 at the locality of attachment thereof to the intermediate cross frame member, uprights secured to said longitudinal frame members and to said intermediate cross frame members to form a rack for the reception of a stack of blanks, said first 40 guide forming a bottom for the rack, a plate-like separator disposed upon the underside of said second named guide and adapted to be moved in between the lowermost blank and the adjacent blank, a plate-like ejector disposed upon the lowermost guide and adapted to engage an edge of the lowermost blank, and means for guiding said separator and ejector for movement along 45 said guides, said guides being positioned so that the lowermost surface of said separator and the uppermost surface of said ejector are substantially coplanar.

4. In combination, a rack for supporting a stack of blanks, a separator movable laterally of the stack to separate the end blank from the adjacent blank, a stop for restraining movement of the blanks in the stack during entry of the separator between the blanks, an ejector movable in the same direction as the separator for ejecting the end blank from the stack, and means operated by said ejector for rendering said stop inoperative.

5. In combination, a frame, a rack for supporting a stack of blanks carried by said frame, a separator movable laterally of the stack and adapted to enter in between the end blank and the adjacent blank, a lever pivoted to said frame, a stop carried by said lever and movable into obstructing and non-obstructing position to control the ejection of blanks from the stack, an ejector movable in the same direction as the separator for ejecting the end blank from the stack, and a cam carried by said ejector for swinging said lever to bring the stop into unobstructing position.

6. In combination, a rack for a stack of blanks, guide means below the rack extending transversely of the stack and supporting the blanks, a separator movable laterally of the stack and parallel to the guide means to separate the end blank from the adjacent blank, and an ejector movable along the guide means in the same direction as the separator and engaging an edge of the lowermost blank of the stack, said ejector sliding along the guide means and ejecting the blank from the stack.

7. In combination, a rack for a stack of planiform blanks each arranged in a substantially horizontal position, guide means below the rack extending transversely of the stack, a plate-like separator movable laterally of the stack and parallel to said guide means and between the lowermost blank and the adjacent blank and supporting the stack above the lowermost blank, a plate-like ejector having an edge adapted to engage an edge of the lowermost blank and movable along the guide means in a plane parallel to the plane of said plate-like separator, said ejector serving to eject the lowermost blank from the stack while the remainder of the stack is supported by said separator.

8. In combination, a rack for supporting a stack of planiform blanks each arranged in a substantially horizontal position, a plate-like separator guided for movement between the lowermost blank and the adjacent blank for supporting the stack above the lowermost blank, a plate-like ejector positioned below the separator and movable in the same direction as the separator, said ejector having a portion adapted to engage an edge of the lowermost blank for ejecting the same from the stack, the lowermost portion of the separator and uppermost surface of the ejector being substantially coplanar.

9. In combination, a rack for supporting a stack of blanks, a separator movable laterally of the stack to separate the end blank from the adjacent blank, a stop for restraining movement of the blanks laterally of the stack during entry of the separator between the blanks, an ejector movable in the same direction as the separator for moving the end blank laterally from the stack, and means for withdrawing said stop prior to ejection of the end blank of the stack.
